US0D1090123S

(12) United States Design Patent (10) Patent No.: US D1,090,123 S
(45) Date of Patent: * Aug. 26, 2025

(54) DESK

(71) Applicant: ODK TECHNOLOGY PTE.LTD.,
Singapore (SG)

(72) Inventor: Hongbing Zheng, Hangzhou (CN)

(73) Assignee: ODK TECHNOLOGY PTE.LTD.,
Singapore (SG)

() Term: 15 Years

(21) Appl. No.: 29/869,953

(22) Filed: Jan. 13, 2023

(30) Foreign Application Priority Data

Dec. 1, 2022 (CN) 202230805128.0

(51) LOC (15) Cl. 06-03

(52) U.S. Cl.
USPC D6/655.14

(58) Field of Classification Search
